(57) **CLAIM**

The ornamental design for a pacifier, as shown and described.

DESCRIPTION

FIG. 1 is a bottom front perspective view of the pacifier showing our new design.

FIG. 2 is a front elevation view thereof, the rear elevation view being a mirror image thereof.

FIG. 3 is a left side elevation view thereof, the right-side elevation view being a mirror image thereof.

FIG. 4 is a top plan view thereof; and,

FIG. 5 is a bottom plan view thereof.

The equal-length broken lines in the drawings depict portions of the pacifier that form no part of the claimed design.
